PRINTER'S PRESS FURNITURE BASE

Charles F. Dausmann, Hempstead, N. Y., assignor
of one-half to Fred W. Hoch, Brooklyn, N. Y.

Application July 28, 1933, Serial No. 682,677

4 Claims. (Cl. 101—389)

This invention relates to printers' furniture and more particularly consists of a base composed of quads having empty spaces in which spaces, adjustable hooks may be inserted to adjust and register the printing plate. The novel feature is to provide a base to be used for the printing of type and plate in combination.

Other bases are known, but these are limited to printing plates only; they cannot be used when plates and type are to be printed in combination. Some bases in use today provide only for mounted plates being tacked on. This invention combines type and plate, as novel, the type being used in conjunction with the base, in that the type is set then the plate is fastened onto the quads by means of the combination quad and plate registering hook. The quads are also used for spacing type. The plate can be lifted out without unlocking the form. Instead of the old printing quad used in spacing type, specially devised quads are utilized, the old ones being replaced with adjustable quads in respect thereto, whereby tacking is eliminated. The individual principle of quad is employed, and the hook is used in combination with the quad. The quads themselves may take various forms, and different types of hooks may be used.

The invention consists therefore of a quad formed base in which the combination quad and hook may be held, and these hooks in the quads hold the plate to register the same, in close proximity to the type set up, with which the novel base is used in the chase.

The invention will be more fully described hereinafter, embodiments thereof shown in the drawing and the invention will be finally pointed out in the claims appended hereto.

In the accompanying drawing:—

Figure 1 is a plan view of the improved base held in position in a chase, the parts being only partially shown, as the general construction of the parts and their assemblage is well known. In Figure 1 is shown a base made up of quads of square contour;

Figure 2 is a plan view of a quad being of strip material forming spaces between the legs of the strip, which can be made of any length;

Figure 3 is another embodiment of a quad forming a base in which a square outlined quad is provided with a circular bore;

Figure 4 shows a base made of quads having a circular bore and circular corners whereby the curved corners form a circular bore for the entrance of a quad hook;

Fig. 5 is a vertical section taken on line 5—5 of Figure 1;

Fig. 6 is a vertical section taken on line 6—6 of Fig. 1 showing an adjustable hook;

Fig. 7 is a perspective view of a quad having a non-adjustable hook thereon;

Fig. 8 is a quad of semi-circular shape having a circular bore adapted to receive a hook therein; and

Fig. 9 is a perspective view of a quad having 10 circular corners, which quad when placed in multiple form forms a circular bore between the corners of the quad, the central bore of the quad shown in Figure 4 being omitted from the quad shown in Figure 9.

Similar reference characters indicate corresponding parts throughout the several views.

Figure 1 is a plan view of an improved base having part of printers' furniture surrounded by the usual furniture 27 and type 23 held in position by the quoins 21 within the usual chase 20. The base is made up of a plurality of quads. Each of these quads is a rectangular member having square top and bottom and rectangular sides. These quads are placed adjacent to each other 25 so as to contact and they may fill up either the entire space, or spaces may be provided between the quads. In the embodiment shown in Figures 1 and 5, the quads are of rectangular shape and have no hooks save four quads three of which 30 are shown in Figure 1. This improved quad shown in perspective in Figure 7, consists of a rectangular body portion 50, having a flat top 51, provided with a hook-shaped portion 52, which has an angular side 53. This improved quad 35 50 is placed alongside of the plate 25 and holds the plate in position in accurate registration. Instead of this non-adjustable hook, an adjustable hook may be provided, as shown in Figure 6, and here a portion 38 is provided with a screw-threaded bore 39 into which a screw-threaded member 40 rotates, having a curved extension 41 which rides on an inclined bottom 37, the portion 38 having flanges engaging the recesses 36. The screw-threaded portion 42 is provided with 45 a recess 43 engaged by a suitable adjusting key, not shown, and the portion 38 has a cross bar 32 having an opening 31, and angular side walls 33 and 34. In the form shown in Figure 6, the angular side 34 engages with the angular side 50 of the plate 25 and holds it in position. No claim is made in this application to the quads having either the non-adjustable or the adjustable hooks, as this is reserved in a case filed of even date herewith. The invention here relates to the 55

base and the base is composed of the similar quads 28 shown in Figures 1 and 5, having hook quads such as shown in Figures 6 and 7, or any other suitable hook quad adjustable or non-adjustable.

Another form of hook quad is shown in the form of Figure 8 where quad 72 has a semi-circular outline or contour and within this quad a bore 73 is provided for an adjustable hook, such as is shown in Figure 6. A still further form of quad is shown in Figure 9, in which the corners of the rectangular member are curved, as shown by the quad 80, having the curved corners 81. When these quads are placed next to each other, the curved corners 81 with the adjacent quads form a circular bore or space into which a hook can be inserted.

These quads may take other shapes. In Figure 2, a strip of material is shown which may be of any length, and when cut into suitable lengths, has legs 61 forming quad spaces 62. Within these square spaces, a hook quad of any suitable type may be inserted so as to hold the plate in position. This M-shaped strip 60 has an extension 61 forming the spaces 62. Another form of quad is shown in Figure 3, in which the quad 64 is provided with a circular opening 66 into which opening or bore an adjustable hook may readily be inserted.

Another form of quad in which the corners are curved, and which is also provided with a central bore, is shown in Fig. 4 by 67 forming circular spaces 69 when four quads are adjacent to each other. The central bore 70 is shown in the axial portion of the quad. Into this circular space 69 or into the central bore 70, one of the forms of the adjustable hooks may be inserted to hold the plate in registration.

It will therefore be noted that the improved base consists of a plurality of quads so arranged as to have spaces into which an adjustable plate registering hook may be inserted. This gives a great deal of flexibility to the base portion and the plate may be readily registered by placing it in position between the type and upon the base. It will be noted that the plate is fastened on to the quads and the quads are used for spacing the type. The invention combines the type and the plate, the type being used in conjunction with the base.

The invention therefore consists of a quad formed base in which quad hooks may be held and these hooks in the quads hold the plate to register the same in close proximity to the type set up, with which the novel base is used in the 5 chase. A base is provided which may be used for printing of the plate and type in combination.

I have described various embodiments of my invention, and I reserve the privilege of resorting 10 to any changes in the details thereof without departing from the spirit and scope of my invention as defined by the appended claims.

I claim:—

1. As a new article of manufacture, a quad of 15 semi-circular contour in transverse section, said quad having a bore, adapted to receive a hook mechanism.

2. In combination a quad of substantially rectangular configuration in plan, said quad having 20 concave recesses at each corner whereby to form a semi-circular recess when two quads are placed in abutting position, and a quad disposed in said recess, said quad being semi-circular in transverse section and provided with a bore adapted to receive 25 a hook mechanism.

3. In combination a quad comprising a body of substantially rectangular configuration in plan, said body having concave recesses at each corner whereby to form a semi-circular recess when two 30 quads are placed in abutting position, said body also having a substantially centrally disposed opening to receive a hook mechanism, and a quad adapted to be disposed in said semi-circular recess, said quad being semi-circular in transverse 35 section and provided with a bore adapted to receive a hook mechanism.

4. As a new article of manufacture, an individual quad of substantially rectangular configuration in plan having a single central bore to 40 receive a hook mechanism and the bore occupying substantially the major area of the quad, said quad having arcuate recesses at each corner whereby to form a full circular centrally disposed bore when four quads are placed in abutting relation, a plurality of quads being disposed in abutting relation to form a printer's base.

CHARLES F. DAUSMANN.
